DISH

Robert W. Schier, Glenview, Ill., assignor to Design
Dynamics, Inc., Northfield, Ill.

Filed Dec. 23, 1971, Ser. No. 211,836

Term of patent 14 years

Int. Cl. D7—01

U.S. Cl. D44—10 A

FIG. 1

FIG. 1 is a top plan view of a dish showing my new design;

FIG. 2 is a bottom plan view thereof, a portion fragmented for convenience of illustration; and

FIG. 3 is a side elevational view thereof.

I claim:

The ornamental design for a dish, as shown and described.
